FLUID PRESSURE BRAKING SYSTEM

Filed June 6, 1938

UNITED STATES PATENT OFFICE

2,239,673

FLUID PRESSURE BRAKING SYSTEM

Owen H. Fowler, Detroit, Mich., assignor to Hydraulic Brake Company, Detroit, Mich., a corporation of California

Application June 6, 1938, Serial No. 212,179

12 Claims. (Cl. 60—54.6)

This invention relates to fluid pressure braking systems, and more particularly to fluid pressure producing devices.

Broadly the invention comprehends a fluid pressure producing device of the compound type having means for transferring the load from one pressure producing means to another without loss after having attained a predetermined pressure.

An object of the invention is to provide a fluid pressure producing device of the compound type operative to attain high pressure without an increase in the applied force.

A feature of the invention is a fluid pressure producing device of the compound type including a cylinder having therein a fixed piston dividing the cylinder into a reservoir and a compression chamber.

Another feature of the invention is a pressure producing device of the compound type including telescopic cylinders, one having therein a fixed piston and the other having therein a reciprocable piston.

Another feature of the invention is to provide a fluid pressure device including a cylinder, a piston reciprocable in the cylinder having on its head a sealing cup, and means for by-passing fluid past the piston to compensate for expansion and contraction of the fluid so constructed and arranged as to avoid injury to the sealing means.

Other objects and features of the invention will appear from the following description taken in connection with the accompanying drawing forming a part of this specification, and in which—

Fig. 1 is a diagrammatical illustration of a fluid pressure braking system embodying the invention;

Fig. 2 is a vertical sectional view of the pressure producing device illustrated in retracted position;

Fig. 3 is a sectional view substantially on line 3—3, Fig. 2;

Fig. 4 is a fragmentary sectional view illustrating the pressure producing device on its compression stroke.

In the drawing, 10 represents a fluid pressure producing device including a cylinder 12, open at one end and closed at its other end by a head 14 having a discharge port 16 controlled as by a two-way valve 18. The cylinder has on its wall adjacent the closed end thereof of a radial flange 20 for mounting the cylinder in a fixed upright position, and arranged in the wall of the cylinder

adjacent the flange is a groove 22 for attaching a flexible dust shield 24. The cylinder also has arranged in its wall on the interior thereof a plurality of spaced slots 26, preferably semi-elliptical. These slots are arranged in a circle, and are suitably spaced from the open end of the cylinder.

A piston 28 reciprocable in the cylinder 12 is held against displacement by a retaining ring 30 seated in a groove 32 in the wall of the cylinder adjacent the open end thereof. The piston has a head 34, a reduced body portion 36 providing in conjunction with the wall of the cylinder an annular chamber 38, and a skirt 40 supporting a concentric rod 42 channeled as indicated at 44 and provided with a reduced end 46. The head 34 has a plurality of spaced passages 48 therethrough providing communications between the annular chamber 38 and that portion of the cylinder forward of the piston, and the skirt 40 has a plurality of spaced passages 50 therethrough providing communications between the annular chamber 38 and the open end of the cylinder.

25 A sealing cup 52 on the head of the piston controls the passages 48 in the head, and a spring 54 interposed between the sealing cup 52 and the two-way valve 18 serves to retain the cup and valve against displacement and also to return the piston to its retracted position. When the piston is in its retracted position, it seats on the retaining ring 30 with its head and the sealing cup 52 thereon intermediate the overall length of the slots 26, so that fluid in the cylinder may 35 freely by-pass the piston.

A cylinder 56, open at one end and closed at its other end as by a head 58, has in its head a filling opening 60 normally closed by a plug 62 having a socket 64, the purpose of which will hereinafter appear, and a plurality of openings 66 through the plug for venting the cylinder to the atmosphere. The cylinder 56 is mounted for reciprocation on the cylinder 12, and movement of the cylinder 56 is limited by a stop 68 mounted in the wall thereof and received by a slot 70 in the wall of the cylinder 12. The cylinder 56 has in its wall adjacent its open end a groove 72 for the attachment of the flexible dust shield 24, and a sealing cup 74 seated on the open end of the cylinder 12 with its lip engaging the wall of the cylinder 56 inhibits seepage of fluid between the cylinders.

40 The cylinder 56 has an internal shoulder 76, and seated on this shoulder is a fixed piston 78

dividing the cylinder into a compression chamber 80 forward of the piston and a reservoir 82 back of the piston. A sealing cup 84 seated on the piston and engaging the wall of the cylinder inhibits seepage of fluid past the piston, and a spring 86 interposed between the cup 84 and the cup 74 carried by the cylinder 12 serves to retain the cups in position and also to return the cylinder 56 to its retracted position wherein it seats on the stop 68.

The fixed piston 78 has a concentric recess 88 opening into the compression chamber 80, and an axial passage 90 therethrough providing a communication between the compression chamber 80 and the reservoir 82. The passage 90 is controlled by a gravity valve 92, held against displacement by a retaining ring 94 seated in a groove in the wall defining the recess 88.

As shown, the gravity valve includes a disk 96 slidable in the recess 88 between the retaining ring 94 and the perimeter defining the passage 90. The disk has a plurality of openings 98 therethrough for the passage of fluid when the valve is open, and when the valve is closed the disk seats on a flexible washer 100 supported on the perimeter defining the passage 90 and effectively seals the openings 98 and also the passage 90.

The disk 96 carries a valve 102 including a valve chamber 104 having a port 106 providing a communication between the compression chamber 80 and the reservoir 82, and a ball valve 108 in the valve chamber for controlling the port urged to its seat by a spring 110 interposed between the ball and a hollow plug 112 secured in the valve chamber.

A fluid pressure delivery pipe or conduit 114 suitably connected to the discharge port 16 of the cylinder 12 has branches connected respectively to fluid pressure actuated motors 116, preferably arranged in pairs, one pair for actuating the brakes associated with the front wheels of the vehicle and another pair for actuating the brakes associated with the rear wheels of the vehicle.

The brakes preferred include a fixed support or backing plate 118 adapted to be secured to an axle or to an axle housing, a rotatable drum 120 associated with the backing plate adapted to be secured to a wheel, a pair of corresponding interchangeable friction elements or shoes 22 pivoted on the backing plate for cooperation with the drum, a retractile spring 124 connecting the shoes, and a motor corresponding to the motors 116 mounted on the backing plate and connected to the shoes for actuation thereof against the resistance of the retractile spring into engagement with the drum so as to effectively retard rotation of the drum.

A thrust rod 126 has one of its ends seated in the socket 64 of the plug 62 secured in the head of the cylinder 56, and its other end pivotally attached to a foot pedal lever 128 mounted on a stub shaft 130 and connected by a retractile spring 132 to a fixed support 134.

In a normal operation, upon depressing the foot pedal lever 128, force is transmitted therefrom through the thrust rod 126 to the cylinder 56, resulting in movement of the cylinder on its compression stroke.

During the initial movement of the cylinder 56 on its compression stroke, the gravity valve 102 closes, and thereafter fluid in the compression chamber 80 forward of the fixed piston 78 is displaced therefrom through the ports 58 in

the skirt of the movable piston 28 into the annular chamber 38, thence through the passages 26 in the wall of the cylinder 12 into that portion of the cylinder 12 forward of the piston 28, and thence past the two-way valve 18, through the discharge port 16 and fluid pressure delivery pipe 114 and its respective branches into the fluid pressure actuated motors 116, causing energization of the motors, resulting in actuation of the respective brakes.

Upon attaining a predetermined pressure in the system, the cylinder 56 has moved sufficiently for the reduced end portion 46 of the rod 42 on the piston 28 to enter the passage 106 and engage the ball valve 108, and thereafter as the cylinder 56 advances on its compression stroke the applied force is transmitted therefrom through the fixed piston, the valve 102 and the rod 42 to the piston 28, resulting in movement of the piston 28.

Upon the initial movement of the piston 28, the sealing cup closes the passages 26, and thereafter the pressure on the fluid is received by the piston 28. As the pressure on the fluid is transferred to the piston 28, the ball valve 108 is urged from its seat by the reduced end 46 on the rod 42, and the fluid in the compression chamber 80 is displaced therefrom through channels 44 and port 106, past the valve 108, into the reservoir 82. Because of the transfer of pressure on the fluid in the system from the large fixed piston 78 to the small movable piston 28, an increase of pressure on the fluid may be attained without an increase in the applied force.

Upon the conclusion of a braking operation, the foot pedal lever 128 is released, and is returned to its retracted position under the influence of the retractile spring 132 carrying with it the thrust rod 126. This results in release of the cylinder 56, whereupon the cylinder is returned to its retracted position under the influence of the spring 86. This movement of the cylinder 56 results in closing of the ball valve 108 and opening of the gravity valve 102 so as to establish communication between the compression chamber 80 and the reservoir 82 by way of the passage 90.

During this operation the piston 28 is returning to its retracted position under the influence of the spring 54, and as the piston 28 returns to its retracted position a partial vacuum is created in the cylinder 12 forward of the piston 28. This results in drawing fluid from the reservoir 82 past the gravity valve 102 into the compression chamber 80, thence through the passages 58 in the skirt of the piston 28, through the annular chamber 38 and the passages 48 in the head of the piston 28, past the sealing cup 52 into that portion of the cylinder 12 forward of the piston, completely filling the cylinder, and simultaneously with this operation fluid is returning to the cylinder 12 from the fluid pressure actuated motors 116 under the influence of the retractile springs 124 connecting the shoes of the respective brakes.

This may result in the cylinder 12 receiving a quantity of fluid in excess of the quantity required to completely fill the cylinder, and under such condition the excess fluid is displaced therefrom through the passages 26, into the annular chamber 38, thence through the passages 58 into the compression chamber 80 and the reservoir 82 communicating therewith. It will be readily apparent from Figs. 2 and 3 that the contour of slots 28 in the plane of the interior wall of cyl-

inder 12 will be elliptical and hence wear of the sealing cup 52 during travel thereof within the cylinder will be reduced to a minimum because the edges of the slots are angularly related to the cup.

Although this invention has been described in connection with certain specific embodiments, the principles involved are susceptible of numerous other applications that will readily occur to persons skilled in the art. The invention is, therefore, to be limited only by the scope of the appended claims.

Having thus described the various features of the invention, what I claim as new and desire to secure by Letters Patent is—

1. A fluid pressure producing device comprising telescopic casings closed at their outer ends, the inner casing having a discharge port, the outer casing having a filling opening, a piston fixedly secured in the outer casing intermediate the ends thereof dividing the casing into a reservoir and a compression chamber, means engaging the closed end of the outer casing for moving the latter, and a reciprocable piston in the inner casing actuated by the fixed piston after a predetermined movement of the outer casing.

2. A fluid pressure producing device comprising telescopic casings closed at their outer ends, means securing the casings together and providing for limited relative movement, means for filling the casings, a discharge port for the inner casing, a piston fixedly secured in the outer casing intermediate the ends thereof dividing the casing into a reservoir and a compression chamber, means providing communication between the reservoir and the compression chamber, means engaging the closed end of the outer casing for moving the latter, and a reciprocable piston in the inner casing actuated by the fixed piston after a predetermined movement of the outer casing.

3. A fluid pressure producing device comprising telescopic cylinders closed at their outer ends, means securing the cylinders together and providing for limited relative movement, the outer cylinder having a filling opening, the inner cylinder having a discharge port, a fixed piston in the outer cylinder dividing the cylinder into a reservoir and a compression chamber, the fixed piston having a passage therethrough, a valve controlling the passage, and a reciprocable piston in the inner cylinder actuated by the fixed piston after a predetermined movement of the outer casing and having a part adapted to engage and open the valve.

4. A fluid pressure producing device comprising telescopic cylinders closed at their outer ends, means securing the cylinders together and providing for limited relative movement, the closed end of the outer cylinder having a filling opening, a plug normally closing the opening, the closed end of the inner cylinder having a discharge port, a fixed piston in the outer cylinder dividing the cylinder into a reservoir and a compression chamber, a valve in the fixed piston providing a communication between the reservoir and the compression chamber, and a reciprocable piston in the inner cylinder actuated by the fixed piston after a predetermined movement of the outer casing and having a part adapted to open the valve.

5. A fluid pressure producing device comprising telescopic cylinders closed at their outer ends, means securing the cylinders together and providing for limited relative movement, the closed

end of the outer cylinder having a filling opening and a plug normally closing the opening, the closed end of the inner cylinder having a discharge port, a valve for control of the port, a fixed piston in the outer cylinder dividing the cylinder into two chambers, a sealing cup on the fixed piston, a valve for control of an opening through the fixed piston, a sealing cup carried by the inner cylinder, a spring interposed between the cups, a reciprocable piston in the inner cylinder, a plunger carried thereby for tripping the valve in the fixed piston, the reciprocable piston having passages therethrough, a sealing cup on the reciprocable piston controlling the passages, means for by-passing fluid around the reciprocable piston when in retracted position, and a spring interposed between the sealing cup on the reciprocable piston and the valve controlling the discharge port.

20 6. A fluid pressure producing device comprising telescopic cylinders closed at their outer ends, means securing the cylinders together and providing for limited relative movement, the outer cylinder having a filling opening, the inner cylinder having a discharge port, a fixed piston in the outer cylinder dividing the outer cylinder into a reservoir and a compression chamber, a controlled passage through the piston, a sealing cup on the piston, a sealing cup carried by the inner cylinder, and a spring interposed between the cups.

30 7. A fluid pressure producing device comprising telescopic cylinders closed at their outer ends, the closed end of the outer cylinder having a filling opening, the closed end of the inner cylinder having a discharge port, means securing the cylinders together and providing for limited relative movement, a fixed piston in the outer cylinder dividing the cylinder into a reservoir back of the piston and a compression chamber forward of the piston, a sealing cup on the piston, a passage through the piston providing a communication between the reservoir and the compression chamber, a two-way valve controlling the passage, a sealing cup carried by the piston, a sealing cup carried by the inner cylinder, and a spring interposed between the cups.

40 8. A fluid pressure producing device comprising telescopic cylinders closed at their outer ends, the closed end of the outer cylinder having a filling opening normally closed by a plug, the closed end of the inner cylinder having a discharge port, a valve controlling the discharge port, a fixed piston in the outer cylinder dividing the cylinder into a reservoir back of the piston and a compression chamber forward of the piston, a passageway through the piston, a two-way valve for control of the passageway, a sealing cup carried by the piston, a sealing cup carried by the inner cylinder, a spring interposed between the cups, a piston reciprocable in the inner cylinder actuatable by the fixed piston, controlled means for by-passing fluid through the reciprocable piston in one direction, means for by-passing fluid past the reciprocable piston in both directions, and a spring interposed between the reciprocable piston and the valve controlling the discharge port.

50 9. A fluid pressure producing device comprising telescopic cylinders closed at their outer ends, the outer cylinder having a filling opening normally closed by a plug and the inner cylinder having a discharge port, a fixed piston in the outer cylinder having an axial passage therethrough, a two-way valve controlling the pas-

sage, said piston dividing the outer cylinder into a reservoir back of the piston and a compression chamber forward of the cylinder, a sealing cup on the piston, a sealing cup carried by the inner cylinder, a spring interposed between the cups, a piston reciprocable in the inner cylinder having passages therethrough, a sealing cup on the reciprocable piston controlling the passages therethrough, means for by-passing fluid past the reciprocable piston in both directions when the piston is at rest, means carried by the reciprocable piston for tripping the valve in the fixed piston and for transmitting force from the fixed piston to the reciprocable piston, and a spring interposed between the cup on the reciprocable piston and the valve controlling the discharge port.

10. In a fluid pressure producing device, a large cylinder open at one of its ends and having a closure for its other end, means directly engaging the closure for actuating the cylinder, a fixed piston in the cylinder dividing the cylinder into a reservoir between the closure and the back of the piston and a compression chamber forward of the piston, a controlled passage through the piston, and a relatively small cylinder telescoping the large cylinder having its inner end open and its outer end closed and provided with a discharge port.

11. In a fluid pressure producing device, a large cylinder closed at one end and open at its other end, the closed end having an opening, a plug for closing the opening having a socket for the reception of a thrust pin and openings for venting the cylinder, a fixed piston in the cylinder dividing the cylinder into two chambers, a controlled passage through the piston, a relatively small cylinder received by the large cylinder having its outer end closed and provided with a discharge port.

12. In a fluid pressure producing device, a cylinder open at one end and closed at its other end, the closed end having a discharge port, a valve for control of the port, said cylinder having in its wall a plurality of recesses, semi-elliptical in cross-section and also in longitudinal section, said recesses arranged in spaced relation and longitudinally of the cylinder, a piston reciprocable in the cylinder adapted to seat when at rest in the open end of the cylinder, a sealing cup on the head of the piston adapted to straddle the recesses when the piston is at rest, and a spring interposed between the sealing cup and the valve.

OWEN H. FOWLER.
